UNITED STATES PATENT OFFICE.

THOMAS S. BLAIR, JR., OF ELMHURST, ILLINOIS.

FURNACE.

No. 927,098.

Specification of Letters Patent.

Patented July 6, 1909.

Application filed February 15, 1909. Serial No. 478,081.

To all whom it may concern:

Be it known that I, THOMAS S. BLAIR, Jr., a citizen of the United States, residing at Elmhurst, in the county of DuPage and 5 State of Illinois, have invented a new and useful Improvement in Furnaces, of which the following is a specification.

My invention relates to an improvement on the feature of Letters Patent No. 869,616, 10 granted to me October 29, 1907, for an improvement in furnaces, which consists of a hollow metal hood covering the port in a reverberatory regenerative furnace, and means for circulating water through the hood to 15 keep it cool.

The primary object of my present invention is to provide, for circulating the cooling-water through the hood, a combination of parts differing from the particular combination thereof shown in the aforesaid patent, 20 comprising a plurality of water-conducting pipes extending within the hood from its outer end and discharging therein at its inner end; and my improvement consists in 25 leading one or more pipes extraneously of the hood, or hollow metal body, to discharge the cooling-medium into the same at its inner-end portion, thus directly to the part which is subjected to the greatest intensity 30 of heat in the furnace, from which to circulate it through the hood to an outlet suitably located therein.

In the accompanying drawings, Figure 1 is 35 a broken longitudinal vertical section showing one of two similar port-containing end-portions of a reverberatory regenerative furnace equipped with my improvement; Fig. 2 is a section on line 2, Fig. 1, and Fig. 3 is a view like that presented in Fig. 2, but showing 40 a slight modification.

In each end of the chamber 4 of the furnace, the gas-port 5 is covered by a hollow metal body 6 extending over it from the end-wall 7, and preferably through the latter, as 45 shown, above a recess 8 in its front face, which is covered by a metal water-back 9 having a water-discharge pipe 10 leading from its lower end, and through which and the wall a manhole 11, provided with a re- 50 movable cover 12, is shown to be formed. The hollow metal body 6 is shown in its pre-ferred form of a hood of the shape illustrated, and is constructed of plate-metal, or it may be a casting of suitable metal; and it pro- 55 jects inclinedly into the furnace, wherein its inner-end portion is supported by the wall-

sections 13. As I construct the hood, of riveted boiler-plates, it is formed of a flanged end-section 14 riveted in place between a top-section 15 and a bottom-section 16 hav- 60 ing a return-bend at its inner end, the ex-tremity of which is deflected to overlap the inner end of the top-section, where the parts are riveted together, as represented in Fig. 1, thereby forming a joint 17. This joint re- 65 quires protection, and to that end it is cov-ered with suitable insulating material 18, preferably a hardened mass of ground mag-nesite, which may be extended, as shown, to cover the entire top surface of the hood with 70 the advantage of insulating it from the heat, especially in the return-flow of the hot gases through the port, and thereby saving in the quantity of water required for keeping the 75 hood cool.

The cooling-water is led to the hood from a suitable source of supply (not shown) through pipes 19, 19, penetrating the wall-structure of the furnace to extend, as shown in Fig. 2, along the opposite sides of the hood, 80 or they may extend at any suitable angles to the hood, as at the right-angle representation in Fig. 3, in any case to be extraneous thereof and discharge into it at or near its inner-end portion, thus directly into the part of the hood 85 which is subjected to the greatest intensity of heat. If desired, a single pipe 19 of suitable diameter, instead of two or more pipes, may be used to direct the water into the hood in a manner to cause its flow through the same 90 and discharge through an outlet-pipe 20, provided in its rear end, or at any suitable point, for keeping the hood cool and thereby preserving it against rapid destruction under the great heat to which its use subjects it. 95

As in my said former patent, the discharge of the cooling-water from the hood is directed through the pipe 20 upon a metal back or "bulk-head" with which each end of the furnace is equipped, to preserve it against 100 rapid destruction by keeping it cool, though if the water be not used for that purpose it may be caused to discharge to any other suitable point, as to a sewer. The form of the metal back herein shown is a modifica-tion of the one shown and described in my 105 aforesaid patent, being that which I have adopted and applied to use, by way of prefer-ence, as a covering for the outer surface of the recessed portion of the port-wall or end-wall, 7, thus leaving the end-wall in place, since it saves in the quantity of water re-

quired for exerting its cooling purpose upon the part 9. Moreover, the box-like form of the present metal back dispenses with the troughs and shelves projecting from the outer face of the metal port-wall, shown in the aforesaid patent, for baffling the flow of water upon the wall, and thus affords a materially greater head for the flow at the discharge-pipe 10, thereby adapting it to be used to much greater advantage in flowing it, for its sealing function as well as its cooling influence, upon apparatus for reversing the direction of the gas and air, which is not herein shown but is commonly employed in the present type of furnace, occupying a plane below that in which the pipe 10 extends.

What I claim as new and desire to secure by Letters Patent is--

1. In a reverberatory regenerative furnace, the combination with a gas-port, of a hollow metal body projecting into the furnace from its end-wall to cover the gas-port and provided with an outlet, and a pipe extraneous of said body directly delivering and flowing through said body a cooling-medium, for the purpose set forth.

2. In a reverberatory regenerative furnace, the combination with a gas-port, of a hollow metal body projecting into the furnace from its end-wall to cover the gas-port and provided with an outlet, and a pipe leading extraneously of said body into its inner-end portion to direct thereto and flow through said body a cooling-medium, for the purpose set forth.

3. In a reverberatory regenerative furnace, the combination with a gas-port, of a hollow metal hood projecting into the furnace from its end-wall to cover the gas-port and provided with an outlet in its rear-end

portion, and a water-pipe leading extraneously of said hood directly to its inner-end portion to flow water thence through the hood, for the purpose set forth.

4. In a reverberatory regenerative furnace, the combination with a gas-port, of a hollow metal hood projecting into the furnace from its end-wall to cover the gas-port and provided with an outlet, and water-pipes leading lengthwise along the hood extraneously thereof and connecting with its inner-end portion to discharge therein and flow water through the hood, for the purpose set forth.

5. In a reverberatory regenerative furnace, the combination with a gas-port, of a hollow metal hood projecting into the furnace from its end-wall to cover the gas-port and provided with an outlet, said hood being composed of united sections and having a joint on its upper side, insulating material on the upper side of the hood covering said joint, and a pipe leading into the inner-end portion of the hood to flow water thence through it, for the purpose set forth.

6. In a reverberatory regenerative furnace, the combination with a gas-port, of a hollow metal hood projecting into the furnace from its end-wall to cover the gas-port and provided with an outlet, said hood being composed of united sections and having a joint on its upper side, insulating material on the upper side of the hood covering said joint, and a pipe leading extraneously of the hood to its inner-end portion to flow water thence through it, for the purpose set forth.

THOMAS S. BLAIR, JR.
